UNITED STATES PATENT OFFICE.

ARON KATZ, OF CHARLOTTENBURG, GERMANY, ASSIGNOR TO SIEMENS & HALSKE,
A. G., OF BERLIN, GERMANY, A CORPORATION OF GERMANY.

AUTOMATIC TELEPHONE-EXCHANGE.

1,172,365.

Specification of Letters Patent.

Patented Feb. 22, 1916.

Application filed January 28, 1913. Serial No. 744,722.

To all whom it may concern:

Be it known that I, ARON KATZ, a citizen of the Austrian Empire, and residing at Charlottenburg, near Berlin, Germany, have 5 invented certain new and useful Improvements in or for Automatic Telephone-Exchanges, of which the following is a full, clear, and exact description, reference being had to the accompanying drawing, forming 10 a part of this specification.

Junction lines in telephone systems provided with selectors can be divided into two groups, namely those having "directed" and those having "non-directed" junction lines.

15 To the former belong for instance the junction lines which go from a selector group to the first thousand, second thousand, etc.; to the latter belong the junction lines which go from preselectors to first group selectors.

20 The "directed" junction lines usually go from selectors, which are set by a number of impulses corresponding to that of a wanted subscriber, these number impulses being controlled by the calling subscriber.

25 In automatic systems hitherto used "non directed" trunks are usually inserted between the calling station *i. e.* subscriber or sub-exchange and the first connecting switch and between the single subsequent connecting switches respectively the number of such different switches used in series for each connection being dependent on the type and range of the exchange system, whereby said switches may be subdivided into pre-

30 selectors, selectors or group selectors and connectors accordingly. These "non directed" junctions or trunks are set independently of the desired direction. This arrangement has the drawback that each of

35 said connecting switches is taken into use, without being certain that over this connecting switch a junction line can be reached which goes in the desired direction. Hence it is usual to insert an automatic selection

40 after a set of impulses, this automatic selection enabling one of 10-20 junction lines in the required direction to be selected. This selection from among a comparatively large number of similar junctions requires connecting switches having many contacts and thereby (especially during rush hours) the arms of the connecting switches have to be moved over considerable distances, causing considerable wear and tear and also loss of

45 50 55 time. A further disadvantage of this usual

system of grouping is that all the junctions going in one direction from any connecting switch may be engaged and if that is the case further connections to be set up over these connecting switches in the same direction cannot be completed, and yet in other groups there are junctions in the same direction which are disengaged.

According to the invention the simplest possible means are provided for giving each 60 calling station access to every one of the "directed" junctions, and means are also provided by which the connecting switches need only have a few contacts and are only taken into use when it is quite certain that they 70 can be used to extend the connection in the desired direction.

A feature of the invention is the testing arrangement for determining, before any of the different connecting switches is taken 75 into use, that a junction line, outgoing from the group of connecting switches is still available.

The connecting switches of each kind shown in the drawings can be of any convenient type and can be operated in any convenient manner. Further their motion can either be controlled by number impulses or it can be automatic. Also any known testing arrangements can be used. Thus for 80 85 instance the connecting switches can have testing magnets which are energized when a disengaged line is found or they can then be deenergized.

For the sake of simplicity the connecting 90 switches are in the drawings provided with only a few lines. Of course larger numbers of lines can be used and when a group contains only two lines, relays can be used as connecting switches.

In the drawings illustrations of the invention are shown.

Figure 1 shows diagrammatically an arrangement of trunk lines between three subsequent connecting switches, of which by way of example the first may be a preselector, the second a group selector and the third a connector, and testing means, in form of separate connecting switches associated therewith, Fig. 2 a modification of 100 the arrangement of Fig. 1 having more outgoing junctions or trunk lines as incoming in the first group of connecting switches, Fig. 3 a modification illustrating the bunching of the trunk lines in the different groups 105 110

of connecting switches, Fig. 4 another modification, in which the connecting switches are provided with three contacts each. Figs. 5 and 6 show the circuit arrangements necessary for setting up a connection between two subscribers.

In the drawings single lines represent junction lines. These lines sometimes represent junctions with two leads and sometimes junctions with three leads. The number of leads depends on the type of system used for setting and testing, whether for example a three wire or loop system is used for setting the connecting switches and whether repeaters and registers are used and so on. If such details were shown it would only confuse the main feature of the invention and it is obvious in what manner the necessary speaking, testing registering release and locking circuits can be added.

Fig. 1 shows a system having 16 lines. The calling lines bear the letter "u" those belonging to the group V, are " u_{11} ", " u_{12} ", " u_{13} ", " u_{14} ", those to group V_2 are " u_{21} ", " u_{22} ", " u_{23} ", " u_{24} ".

Each calling line has a connecting switch, which may be a preselector and likewise bears the letter "u" and there is also a second connecting switch allotted to each calling line which bears the letter "w", rather called a testing switch as will be seen later on. The connecting or testing switches "w" are arranged in groups D.

The junction lines "v", outgoing from groups V, terminate in selectors $g_1, g_2, \dots$ which are arranged in groups G_1, G_2, G_3, G_4 , each comprising four selectors. The junctions are so arranged that those outgoing from a V group each terminate in a different G group. Similarly the junction lines "d" outgoing from a D group terminate in connecting switch "q" likewise called testing switches which are arranged in groups $P_1, P_2, \dots, P_4$, the junction lines from a D group likewise terminating in different $P_1, P_2, \dots$ groups. The junctions $r_1, r_2, \dots$ outgoing from the groups G similarly terminate in selectors, which may be connectors and are arranged in groups L, the junctions from a group G, as before terminating on different groups $L_1, L_2, \dots$. The junctions $p_1, p_2, \dots$ outgoing from the P groups are joined to the junctions from G to L in such a manner that those outgoing from P_4 are joined to the junctions r_4, r_8, r_{12}, r_{16} belonging to the final group L_4 . The lines outgoing from L_4 can be subscribers' lines or they can be junctions going to other groups in the same exchange or other exchange.

If a connection is to be set up between the lines u_{24} and t_{43} (Fig. 1) the calling station u_{24} will first, by means of four current impulses set the selector w_{24} of the group D_2 on to the group P_4 , thereby oc-

cupying the junction d_8 . By means of the circuit shown in Fig. 5 the testing switch q_8 , which is allotted to the junction d_8 in the group P_4 , is coupled with the preselector u_{24} in the group V_2 , and both begin to move 70 synchronously. Assuming now that the junctions v_5, v_6, r_8, r_{12} , are already engaged, then after both switches have moved one step, the preselector u_{24} is set on junction v_5 and the testing switch q_8 is set on r_4 . By 75 means of the arrangement shown in Fig. 5 the switches cannot stop there, because the preselector u_{24} has reached an engaged line (V_5) although the junction r_4 is disengaged. Both switches therefore move on another 80 step and they reach junctions v_6 and r_8 both of which are engaged, hence the switches take a third step.

Although the junction v_7 is disengaged yet the switches have again to move on, 85 because the junction r_{12} is engaged. They then reach the junctions v_8 and r_{16} which are simultaneously disengaged. As soon as by this doubling testing operation at V and P a group G''' has been found, which can be reached from an available non-directed junction and which has an outgoing junction r_{16} available in the desired direction L_4 the connecting switches come to rest and the testing switches in the groups D and P are available for other calls, this being effected in the manner shown in Fig. 5. From the calling station u_{24} or from any other station the selector g_{24} in the group G''' is now set on the line r_{16} . The number of 100 impulses which the connecting switch g_{24} receives corresponds to the desired direction L_4 . The junction r_{16} terminates in the connector l_{16} which is set on the desired line t_{43} by means of a second set of three number-impulses sent by the calling station u_{24} . The speaking lines are thus from u_{24} over $v_8, g_{21}, r_{16}, l_{16}$ to t_{43} .

If other v and r junctions than those assumed above had been engaged, the connection might then have been set up over the group G_1 or G_2 because a pair of junctions v and r have to be found which belong to the same group and are simultaneously available. It is immaterial which groups 115 of the selectors G_1, G_2 are used.

The arrangement according to Fig. 1 has the disadvantage that under some circumstances it would be possible that the connection could not be set up although there 120 are free junctions. When for instance the junctions v_5, v_7 and v_8 are engaged, then no pair of junctions is free having junctions v and r belonging to the same group and simultaneously available. In order to overcome this defect the groups V allotted to the calling station u are allotted more (for instance double as many) outgoing junctions as there are junctions incoming in the groups V. This is shown in Fig. 2. The 125

lines v_1-v_{32} terminate in groups G. The junctions v_1-v_{32} can then go to groups G having twice as many selectors as the groups V preselectors. But instead of this there could be twice as many groups G as there are groups V and then each of these groups would have only as many selectors as the group V preselectors. In any case the groups have as many outlets as the groups V. When the groups have twice as many 5
selectors as groups V, then there are two junctions from each group V to each group G. If however there are twice as many groups G as there are groups V, then there is only one junction from each group V to each group G. Under these circumstances the final group L will have more inlets than outlets, for instance twice as many incoming junctions r and connectors than 10
going junctions t. The groups D and P can be more simple because the switches and junctions of these groups are only occupied till the end of the synchronous testing. One can now assume that any desired 15
number of junctions are engaged and nevertheless there will always be a disengaged pair of junctions v and r. For instance from the group V_2 it will be assumed that three connections have been set up and that 20
the junctions v_9, v_{10}, v_{11} are engaged. Thereby the group G_1 is unavailable for further calls from the group V_2 because v_9 and v_{10} are engaged. It will be assumed 25
now that of the junctions r those $r_{23}, r_{24}, r_{31}, r_{32}$ are engaged. Hence there will be no outlet from the groups G_3 and G_4 to the group L_4 . There therefore remains only one path namely that over group G_2 , the junction v_{12} , and the junction r_{15} or r_{16} . 30
This path will be found by the synchronous testing of switches V and P in the same manner as before described.

In order to prevent any misconception let it be assumed that the junctions v_9, v_{10}, v_{11} and v_{12} are engaged and likewise the junctions $r_{23}, r_{24}, r_{31}, r_{32}$. The groups G_1 and G_2 therefore cannot be reached from the group V_2 because v_9-v_{12} are engaged and the groups G_3 and G_4 cannot be reached for setting up a connection in the direction L_4 because the junctions $r_{23}, r_{24}, r_{31}, r_{32}$ are engaged. This therefore does not seem to agree with the above statement that an available 45
pair of junctions (v, r) can always be found. This is however not the case because there cannot be more than four connections set up in the group V_2 which according to the above assumption can be set up over the junctions v_9-v_{12} . The arrangement according to Fig. 2 therefore under all circumstances permits a free pair v, r of junctions to be found. When as in the above assumption $r_{23}, r_{24}, r_{31}, r_{32}$ are engaged then a call could reach the 50
group L_4 over the junctions v_{12}, r_{15} , (or r_{16})

but the connectors in the group L_4 will find that the desired line t_{43} is already engaged.

In the arrangement according to Figs. 1 and 2 the junctions v and p (i. e. r) are separately successively tested. When the 70
switches have a large number of junctions this method of testing will take too much time. In Fig. 3 the bunching of the junctions v and r in the groups is diagrammatically shown.

The switches are assumed to have nine positions, the designations used are similar to those in Figs. 1 and 2. Thus for instance the junctions v_{10}, v_{11}, v_{12} go to the groups G_1, G_2, G_3 . Similarly the junctions p_{91}, p_{92}, p_{93} , in the group P_9 , go to the junctions r_{19}, r_{29} and similarly p_{94}, p_{95}, p_{96} go to r_{39}, r_{49} , etc. When one of these junctions for instance v_{10} is engaged its relay (not shown) will be energized and contact k_1 closed. If v_{11}, v_{12} are also engaged the contacts k_{11} and k_{12} of relays which are not shown will be closed and earth is connected to a bus bar s_1 . This bus bar s_1 belongs to a special testing arrangement which is such that when the preselector u reaches the earthed bar s_1 it makes a big step over three contacts. If in a similar manner s_2 is also earthed then the preselector makes a second big step to the junction v_{16} . In similar manner the contacts k_{10}, k_{11}, k_{12} are closed when the junctions r_{19}, r_{29}, r_{39} , are engaged. When the contacts k_{10}, k_{11}, k_{12} are closed, earth is connected to the bus bar s_4 . If now during the testing operation the testing switch q reaches an earthed bus bar s_4 or s_5 it will make a large step over three contacts. When the testing switch q makes a large step then the preselector u synchronously does the same and vice versa. The distinguishing 100
feature of this arrangement is that junctions v and r are bunched in groups namely v_{10}, v_{11}, v_{12} , and similarly the junctions r_{19}, r_{29}, r_{39} , going from groups G_1, G_2, G_3 in the direction to L_4 , are bunched in group s_4 . The same holds good for all other directions.

The fundamental idea is that strictly speaking the testing arrangements in V and P do not test the junctions v and r but the incoming and outgoing lines of the group G. Connecting switches are known which first test the groups and then the individuals in a particular group. An obvious alternative method is to use two smaller connecting switches one behind the other such an arrangement being also well known and is illustrated in Fig. 4. The incoming lines $u_{11}-u_{19}$ terminating in three groups of connecting switches each having three contacts. The junctions x_1, x_2, x_3 from V_1 likewise terminate in three groups Y_1, Y_2, Y_3 , in connecting switches having three contacts. The junctions outgoing from the groups Y correspond to the junctions v in Fig. 3. As before the junctions are arranged three in a 115
120
125
130

group for instance v_1, v_2, v_3 . Each junction v has a relay which is not shown and which closes the contact k when the junction is taken into use. When the contacts k_1, k_2, k_3 are closed, a testing arrangement s_1 is earthed and a switch u testing this contact will step farther from x_1 to x_2 . The individual testing is done by the switches in the group Y .

Fig. 4 diagrammatically shows switches having only three contacts. It is obvious that these can be replaced by an arrangement similar to Fig. 2 in which the possibility of setting up connections between any subscribers is unlimited and for this purpose there will be more lines outgoing from the groups V and the groups Y than lines incoming. In that case the testing arrangement is particularly suitable. The lines t in Fig. 1 could be lines to other groups of switches. For instance a system could be so built up that the group V_1 in Fig. 1 is replaced by the whole arrangement shown in Fig. 1, *i. e.* all the groups V, G, L, D, P . The lines t in Fig. 1 represent the lines r in the enlarged system. In large systems the double selecting operation will be as often repeated as circular arrangements according to Figs. 1, 2 or 3 are connected in series with one another. Instead of using switches having several bank contacts as shown in Fig. 4, two switches having less contacts can be used and these can likewise be connected in series.

Figs. 5 and 6 show by way of example the circuit arrangements necessary which can be used for setting up a connection between two subscribers u_{21} and t_{43} . Each subscriber has allotted to him a preselector V and a testing switch D . When he lifts his receiver the line relay R is energized by current over the loop, and closes at contact 1 the circuit for the time relay VR_1 . When the subscriber u_{21} operates the number dial at his instrument, the motor magnet DM_1 of the testing switch D receives impulses over the circuit from earth, 2, 3, VR_2 , side switch arm s_1 , contact 4, DM_1 , battery, earth. VR_2 is likewise a time relay, it closes at contact 5 the circuit for a side switch magnet S over side switch arm s_{11} . The side switch magnet however only moves the arms on when it is deenergized when 5 is again opened, this arrangement being well known. The operation of DM_1 places the arms 16, 8, 33 in contact with the bank contacts one of which is 15. The following circuit is also completed, earth, 7, 6, 8, off normal contact 9 of the testing switch P , relay VR_4 , battery, earth. VR_4 is energized and at its front contacts 10 and 11 closes the following circuit earth, battery B_2 , normal contact 12 of the contact arm 13 on testing switch P , 11, motor magnet DM_2 of P , relay VR_5 , front contact 10 or after the first step off

normal switch 14 in parallel with it, contact 15, arm 16 of D , s_{11} , 17, junction lead 18, 19, s_{11V} , VR_3 , DM_2 , of preselector V , front contact 20 of VR_3 , arm 21, normal contact 22 of 21, battery B_1 , earth. Thereby the motor magnets move the arms of P and V simultaneously so that 21 is now connected to 23, instead of 22 and 13 to 24 instead of 12.

The testing arrangements are such that a disengaged lead (23 or 24) is earthed over the back contact 25 and 26 of the relays VR_1 and VR_2 . An engaged line has battery B_1 connected to it over front contact 27 and battery B_2 over front contact 28. The testing switches V and P will continue to move till both simultaneously reach a disengaged contact in which case therefore both the leads 23 and 24 will be disengaged. If both the leads 23 and 24 are simultaneously occupied by other switches, the motor magnets will be operated by the batteries B_1 and B_2 connected in series. If however only one of these leads is free the battery B_1 or B_2 is sufficient to operate the switches. Assuming now that the switches V and P have simultaneously reached lines both of which 23 and 24 are disengaged, the circuit for DM_2 , VR_3 , VR_5 , DM_2 is then opened. When VR_3 is deenergized it opens contact 29 and thereby opens the circuit of S . The side switch arms are now moved into position three. Thereby the connection between the preselector V and the testing switch P over the junction lead 18 and the selector D is broken. Further the speaking leads a and b are switched through at 41 and 41'; owing to the deenergizing of VR_3 the contact 30 is opened and thereby the holding circuit of the relay VR_1 over front contact 31 is opened at contact 30. VR_1 releases its armature and at back contact 32 prepares a release circuit for testing switch P . At the arm 33 of D the circuit of an auxiliary relay HR is closed over the off normal switch 34 of P . Then HR will effect the release of testing switch D as described later on. Over the back contact 35 of VR_3 and the front contact 36 of VR_1 the circuit for the time relay VR_1 is closed. VR_1 at its front contact 27 puts the engaged test on the lead 23 by connecting it to battery B_1 . The subscriber u_{21} now again operates his number dial and sets the selector G''' on the same contact as the testing switch D , if for instance the testing switch D has been set on the fourth contact then selector G will likewise be set on the fourth contact. While these number impulses are being sent the side switch magnet S is energized over contact 38 and s_{11} . The current impulses for setting selector G''' pass over the following circuit: earth, 40, a , 41, 42, 43, 44, relay R , 46, battery, earth. By each impulse the contact 2' is closed and thereby the motor magnet DM_4 energized. At the first

- impulse the time relays VR_7 , and VR_{10} are energized. During the transmission of the impulses VR_7 opens contact 70 and contact 45, whereby it prevents the test relay PM_1 being energized during the movement of the selector G''' . At the end of the impulse the relays VR_7 and VR_{10} become de-energized the latter first, as VR_7 is slower acting. Thereby the relay VR_7 holds the contact 70 in the circuit of the relay VR_{10} opened so that the test relay PM_1 is energized and opens the contact 46' in the circuit of the relay VR_{10} before the contact 70 is closed upon the de-energization of relay VR_7 . Thus the motor magnet MD_4 also cannot be again energized upon closing the off normal contact 69, its circuit being broken at the contact 46'. The relay PM_1 opens the contact 46 and de-energizes the relay R_1 . At the end of the impulses after selector G''' has been set the contact 5 is opened and thereby breaks the circuit of S , thereby moving the side switch arms into the fourth position.
- As soon as the side switch arms (s) reach the fourth position the following circuit is closed: earth, U , 47, s_{III} , 16, 15, 14, VR_5 , DM_5 , 32, 48, battery, earth. The testing switch P will move on till it reaches its normal position whereupon the contacts 48 and 14 are opened. When the normal position is reached contact 34 is also opened and thereby circuit for the auxiliary relay HR is opened. HR is de-energized and at 50 completes the circuit of the motor magnet DM_1 of testing switch D as follows: earth, battery, DM_1 , sV , 49, 50, off normal switch 51, interrupter U' , earth. When the selector reaches its normal position switch contact 51 is opened and the selector comes to rest.
- As soon as the selector G has picked out a connector LW (Fig. 6) the relay C at the latter is energized and at 52 closes the circuit of the motor magnet DM_5 . Furthermore the relay C closes the contact 37, whereby a circuit for the relay VR_6 is closed over earth, battery, VR_6 , r_{16} , 37, earth. Upon energization of the relay VR_6 (Fig. 5) disconnects earth from the lead 24 by opening the back contact 2 and connects battery B_2 on the contact 28 to the lead 24. Thereby the circuits of the motor magnets MD_2 and MD_3 of any other testing switches are closed as already mentioned. Impulses are now again sent by the calling subscriber u_{24} through relay R and are repeated over DM_5 and VR_6 the circuit being: earth, 39, 40, a , 41, 42, 43, s_{VI} , 52, DM_5 , VR_6 , battery, earth. VR_6 closes contact 53 and thereby completes the circuit of side switch magnet S_1 . At the end of the impulses 53 is again opened and the side switch arms s'_1-s_{VII} move into the second position in which the testing relay P_2 is at s_{IV} connected to the test arm of the connector for the purpose of testing the wanted subscriber's line.
- Assuming first that the wanted subscriber t_{43} is disengaged, P_2 will be energized and at 54 and 55 connects the special leads 70 through and at contact 56 connects the interrupter U_2 to the side switch magnet S_1 over contact 57 of the side switch arm s'_1 . Thereby the side switch arms are moved to the third position in which the circuit of ringing relay LR is closed: earth, battery, 58, s_{III} , 59, LR , interrupter Sch , earth. LR is periodically energized and when thus energized it, at its front contacts of 60 and 61 connects ringing current to the line. 80 When the wanted subscriber t_{43} answers the call the line relay Y is energized and opens contacts 58, 63 and 66 and closes contact 62. At the back contact of 58 the circuit of ringing relay LR is opened, at 62 VR_9 is energized which at 64 prepares the releasing circuit for the selector G''' . 85
- At the end of the conversation the two subscribers u_{24} and t_{43} hang up their receivers. Assuming that the wanted subscriber 90 hangs up before the calling subscriber the circuit alterations will then be as follows: Relay Y is de-energized and at 66 completes the releasing circuit of M . At 62 the circuit of the time magnet VR_9 is opened, but VR_9 95 retains its armatures for a short time so that contact 54' does not open immediately and current therefore flows from earth, battery, 67, M , 54', 66 to earth, and the connector LW is thereby released. The relay Y at 63 100 connected earth to the lead 65 over 68, 64, 63. The relay P_1 and G is therefore short circuited, and releases its armature which at 46 closed the circuit: earth, battery, DM_4 , VR_{10} , 70, 46', 69, interrupter, earth. The 105 time relay VR_{10} being energized prevents the energization of relay P_1 by opening its contact 45 thereby disconnecting earth from P_1 and the test arm of the selector G''' 110 while the latter is moving over the bank contacts. The selector G''' is rotated by its motor magnet DM_4 , until it reaches its normal position, whereupon the off normal switch 69 and thereby the circuit of DM_4 and VR_{10} is opened. When now the calling 115 subscriber U_{24} hangs up his receiver relays R and VR_1 will in succession be de-energized. The relay VR_1 closes the contacts 72 and 74. At 72 the circuit for motor magnet DM_2 and VR_3 is closed from earth, battery 120 73, 72, DM_2 , VR_3 , s_{IV} , 75, U_4 , earth. Thereby the preselector V is rotated till it reaches its normal position whereupon the contact 73 is opened and the circuit of DM_2 125 thereby opened.
- As soon as the preselector V reaches its normal position its off normal contact 77 closes the following circuit for the release magnet N : earth, battery, N , 76 (which is closed as soon as the side switch s leaves its 130

normal position) 74, 77, earth. The side switch s may only be released after the pre-selector V has reached its normal position, otherwise the circuit of motor magnet DM_2 5 will be opened at 75 of s_{IV} in which case the selector arms could not be moved back to their normal position. It will now be assumed that the wanted subscriber's line is engaged and that therefore the relay P_2 is 10 not energized. In that case the side switch of the connector LW remains in its second position with the busy back buzzer connected to the lead b at contact 78 of s'_{IV} when the calling subscriber hears this signal he hangs 15 up his receiver. Thereby owing to the release of R a single impulse is sent from earth over 39, 40, a , 41, 42 43, s'_{VI} , 52, D_5 , VR_5 , battery, earth. VR_5 is energized and at 20 79 closes the circuit of the release magnet M so that the connector is released. At 64 earth is connected over 81, s'_{II} , 64, 63, to the lead 65 so that as before explained the selector G'''' is likewise released.

In the specification and claims the expression "lines" also groups of lines may be understood in case the telephone system is large enough to use groups. In the same manner "called lines" and "trunk lines" are included in the term called lines.

30 Having explained my invention, what I do claim and desire to secure by Letters Patent is:

1. In an automatic telephone exchange, calling lines, called lines, trunk lines, devices 35 for selecting said called lines, other devices for selecting said trunk lines, and means for testing said trunk lines before said trunk selecting devices select one of said trunk lines.
2. In an automatic telephone exchange, 40 calling lines, called lines, trunk lines leading to said called lines, devices for selecting said trunk lines leading to called lines, and means for testing said lines leading to called lines available for the selecting devices before the latter select a trunk line.
3. In an automatic telephone exchange, 45 calling lines, called lines, trunk lines, electromagnetically operated selecting devices, adapted to be set upon trunk lines leading to called lines, and means for testing said trunk lines leading to called lines available for the selecting devices before the latter select a trunk line.

4. In an automatic telephone exchange, 55 calling lines, called lines, trunk lines selecting devices adapted to be set upon trunk lines leading to called lines, means for testing said trunk lines before they are selected by the selecting devices, and means for connecting a calling line with said selecting devices.
5. In an automatic telephone exchange, 60 calling lines, called lines, trunk lines, selecting devices adapted to be set upon trunk lines leading to said called lines, means for

testing said trunk lines before they are selected by the selecting devices, means for connecting a calling line with said selecting devices, and means for disconnecting the testing means from a trunk line leading to 70 called lines after testing.

6. In an automatic telephone exchange, calling lines, called lines, trunk lines, devices for selecting said called lines, other devices for selecting said trunk lines, means 75 for testing said trunk lines before they are selected by the said selecting devices, and means for connecting a calling line with one of the said trunk selecting devices.

7. In an automatic telephone exchange 80 calling lines, called lines, trunk lines, selecting devices adapted to be set upon said trunk lines, said selecting devices being arranged in groups, and means for testing the outgoing trunk lines of said groups before 85 they are selected by said selecting devices.

8. In an automatic telephone exchange 86 calling lines, called lines, trunk lines, groups of selecting devices adapted to be set upon said trunk lines, means for testing said 90 trunk lines of said groups before they are selected by the selecting device, and means for connecting a calling line with one of the selecting devices in said groups.

9. In an automatic telephone exchange 93 calling lines, called lines, trunk lines, groups of selecting devices adapted to be set upon said trunk lines, means for testing said trunk lines of said groups before they are selected by the selecting devices, means for connecting 100 a calling line with one of the selecting devices in said groups, and means arranged on the calling line to operate said selecting devices.

10. In an automatic telephone exchange, 105 calling lines, called lines, selecting devices, means for testing lines outgoing from selecting devices before they are selected by the selecting devices, said testing means being operated independently of said selecting devices.

11. In an automatic telephone exchange, 110 calling lines, called lines, selecting devices, means for testing the outgoing lines before selected by the selecting devices, and means 115 for connecting the called lines with said selecting devices.

12. In an automatic telephone exchange, 115 calling lines, called lines, selecting devices, and independently movable switches acting 120 as testing means.

13. In an automatic telephone exchange, 125 calling lines, called lines, selecting devices, preselective switches controlled by the calling lines, capable of connecting a calling line with the selecting devices and independently movable switches acting as testing means.

14. In an automatic telephone exchange, 130 calling lines, called lines, selecting devices,

- preselective switches, lines arranged between the preselective switches and the selecting devices, trunk lines leading from the selecting devices to the called lines and means for testing said trunk lines, before they are selected by preselective switches and selecting devices respectively.
15. In an automatic telephone exchange, calling lines, trunk lines, selecting devices for selecting said trunk lines, preselective switches controlled by the calling lines, capable of connecting a calling line with the selecting devices and independently movable switches acting as means for testing said trunk lines leading to called lines.
16. In an automatic telephone exchange, calling lines, selecting devices, preselective switches trunk lines arranged between said selective switches and said selecting devices, trunk lines leading to the called lines, means combined with said preselective switches for testing said trunk lines arranged between said preselective switches and said selecting devices, and means arranged independently of any said switches for testing said trunk lines leading to the called lines.
17. In an automatic telephone exchange, calling lines, called lines, selecting devices, preselective switches, trunk lines arranged between said preselective switches and said selecting devices, trunk lines leading to the called lines, and means being arranged independently from any of said switches and selecting devices, for testing said trunk lines leading to the called lines, having as many testing positions as there are trunk lines.
18. In an automatic telephone exchange, calling lines, called lines, selecting devices, preselective switches, trunk lines arranged between said preselective switches and said selecting devices, trunk lines leading to the called lines, means combined with said preselective switches for testing said trunk lines arranged between said preselective switches and said selecting devices, having as many testing positions as there are trunk lines, and means being arranged independently from any of said switches and selecting devices for testing the trunk lines leading to the said called lines, having as many testing positions as there are trunk lines.
19. In an automatic telephone exchange, calling lines, called lines, selecting devices, preselective switches, trunk lines arranged between said preselective switches and said selecting devices, trunk lines leading to the called lines, means for testing said trunk lines arranged between said preselective switches and said selecting devices, means for testing said lines leading to the called lines, and means for operating the selecting lines, and means for independently of said testing means.
20. In an automatic telephone exchange, calling lines, called lines, selecting devices, preselective switches, trunk lines arranged between said preselective switches and said selecting devices, trunk lines leading to the called lines, means for testing said trunk lines arranged between said preselective switches and said selecting devices, means for testing the trunk lines leading to the called lines, both said testing means being branched off in multiple from said calling lines, and controlled by the calling lines.
21. In an automatic telephone exchange, calling lines, called lines, selecting devices, preselective switches, trunk lines arranged between said preselective switches and said selecting devices, trunk lines leading to the called lines, means for testing said trunk lines arranged between said preselective switches and said selecting devices, means for testing said trunk lines leading to the called lines, both said testing means being arranged in multiple, and means whereby one kind of said testing means is controlled by the other while operating.
22. In an automatic telephone exchange, calling lines, called lines, selecting devices, preselective switches, trunk lines or groups of lines arranged between said preselective switches and said selecting devices, trunk lines leading to the called lines, means for testing said trunk lines arranged between said preselective switches and said selecting devices, means for testing said trunk lines leading to the called lines, and means whereby both kinds of testing means are operated synchronously.
23. In an automatic telephone exchange, calling lines, called lines, selecting devices, preselective switches, trunk lines arranged between said preselective switches and said selecting devices, trunk lines leading to the called lines, means for testing said trunk lines arranged between said preselective switches and said selecting devices, trunk lines leading to the called lines, means for testing said trunk lines arranged between said preselective switches and said selecting devices, means for testing said trunk lines leading to the called lines, and means, whereby both kinds of testing means are stopped synchronously when moving.
24. In an automatic telephone exchange, calling lines, called lines, selecting devices, incoming trunk lines leading from said calling lines to the selecting devices, outgoing trunk lines leading from the selecting devices to said called lines, means for testing said incoming trunk lines, means adapted for testing said outgoing trunk lines, both said testing means being arranged in multiple, and means for interrupting the movement of both said kinds of testing means, when both testing means have found an available respective line.
25. In an automatic telephone exchange, calling lines arranged in groups, called lines arranged in groups, selecting devices ar-

ranged in groups, trunk lines between each of said groups of calling lines and each of said groups of selecting devices, other trunk lines between each of said groups of selecting devices and each of said groups of called lines.

26. In an automatic telephone exchange, calling lines arranged in groups, called lines arranged in groups, selecting devices

19 arranged in groups, trunk lines between each of said groups of calling lines and each of said groups of selecting devices, other trunk lines between each of said

15 groups of selecting devices and each of said groups of called lines, testing means for testing said latter trunk lines arranged in groups separated from any of said other groups and testing lines between said groups of testing means and said groups of

20 called lines, whereby all testing lines outgoing from one of said groups of testing means are incoming testing lines at one of said groups of called lines.

27. In an automatic telephone exchange, 25 calling lines, called lines, selecting devices, trunk lines leading to called lines independent switches for testing the latter lines, and final selecting means arranged in groups between the trunk lines and the called lines.

30 28. In an automatic telephone exchange, calling lines, called lines, selecting devices, trunk lines leading to called lines independently movable switches for testing the latter lines, final selecting means arranged in

35 groups between the trunk lines and the called lines, said testing means having as many testing positions as there are trunk lines between the selecting devices and the corresponding group of said final selecting means.

40 29. In an automatic telephone exchange, calling lines, called lines, selecting devices, preselective switches trunk lines leading to called lines, independently movable switches for testing the latter lines, and final selecting means arranged between the trunk lines and the called lines.

30. In an automatic telephone exchange, calling lines, called lines, selecting devices, 45 preselective switches trunk lines leading to called lines, independently movable switches for testing the latter lines, final selecting means arranged between said trunk lines and the called lines and operated by impulses sent over the calling lines.

31. In an automatic telephone exchange, calling lines, called lines selecting devices, preselective switches trunk lines connecting said preselective switches with said selecting 55 devices, independently movable switches for testing said trunk lines, trunk lines connecting said selecting devices with called lines and independently movable switches for testing the latter trunk lines, and final se-

lecting means arranged between the latter 65 trunk lines and the called lines.

32. In an automatic telephone exchange, calling lines, called lines, selecting devices, means for testing lines outgoing from said selecting devices before they are selected by 70 the selecting devices, and means for connecting the calling lines with said testing means.

33. In an automatic telephone exchange, calling lines, called lines, selecting devices, 75 means for testing lines outgoing from the selecting devices before they are selected by the selecting devices, means for connecting the calling lines with said testing means, and means for disconnecting said testing 80 means from a calling line after testing.

34. In an automatic telephone exchange, calling lines, called lines, selecting devices, means for testing the lines outgoing from said selecting devices before they are selected by 85 the selecting devices, means for connecting the calling lines with said testing means, said connecting means consisting of electromagnets and movable contact fingers driven by said magnets. 90

35. In an automatic telephone exchange, calling lines, called lines, selecting devices, means for testing lines outgoing from said selecting devices before they are selected by the selecting devices, means for connecting 95 the calling lines with said testing means, said connecting means consisting of electromagnets and movable contact fingers driven by said magnets and being operated by impulses controlled by the calling line. 100

36. In an automatic telephone exchange, calling lines, called lines, trunk lines leading to said called lines selecting devices, means adapted for testing said trunk lines, means for connecting the testing means with calling lines, means for connecting calling lines with said selecting devices, means for connecting said selecting devices with said trunk lines leading to called lines, means for disconnecting said testing means from said 105 calling lines and means for disconnecting said testing means from said trunk lines leading to called lines. 110

37. In an automatic telephone exchange, calling lines, called lines, trunk lines leading to said called lines, selecting devices, preselective switches, means adapted for testing said trunk lines, means for connecting the testing means with calling lines, means for connecting said preselective 115 switches with said selecting devices, means for connecting said selecting devices with said trunk lines, leading to called lines, means for disconnecting said testing means from said calling lines and means for disconnecting said testing means from said trunk lines leading to called lines. 120

38. In an automatic telephone exchange,

calling lines, called lines, selecting devices, means for testing lines outgoing from the selecting devices, before they are selected by the selecting devices, means for connecting the calling lines with said testing means and means for connecting the called lines with said selecting devices.

39. In an automatic telephone exchange, calling lines, called lines, selecting devices, 10 preselective switches, means for testing the lines outgoing from the selecting devices, before they are selected by the selecting devices, means for connecting the calling lines with said testing means and means for connecting the called lines with said selecting devices.

40. In an automatic telephone exchange, calling lines, called lines, selecting devices, preselective switches, means for testing the lines outgoing from the selecting devices before they are selected by the selecting devices, means for connecting the calling lines, with said testing means, and controlled by impulses sent over the calling line, and 25 means for connecting the called lines with said selecting devices.

41. In an automatic telephone exchange, calling lines, called lines, selecting devices, preselective switches, means for testing the lines outgoing from the selecting devices before they are selected by the selecting devices, means for connecting the calling lines with said testing means and controlled by impulses sent over the calling line, said testing means being operated independently of said selecting devices and said connecting means, means for connecting the called lines with said selecting devices, said selecting devices being operated independently of said 40 preselective switches.

42. In an automatic telephone exchange, calling lines, called lines, selecting devices, preselective switches, means for testing the lines outgoing from the selecting devices before they are selected by the selecting devices, means for connecting the calling lines with said testing means, trunk lines connecting said selecting devices with called lines, final selecting means arranged between 45 said trunk lines and the called lines and means for connecting a calling line with one of the selecting devices.

43. In an automatic telephone exchange, calling lines, called lines, selecting devices, 55 preselective switches means for testing the lines outgoing from the selecting devices before they are selected by the selecting devices, means for connecting the calling lines with said testing means, trunk lines connecting said selecting devices with called lines, final selecting means arranged between 60 said trunk lines and the called lines, and means for connecting a calling line with one of the selecting devices, said connecting

means being operated independently of the calling lines.

44. In an automatic telephone exchange, calling lines, called lines, selecting devices, trunk lines arranged between said selecting devices and said called lines, means for testing said trunk lines before they are selected by the selecting devices, said trunk lines being arranged in groups and subgroups.

45. In an automatic telephone exchange, calling lines, called lines, selecting devices, 75 preselective switches, trunk lines arranged between said preselective switches and said selecting devices in groups and subgroups, trunk lines arranged in groups and subgroups between said selecting devices and 80 said called lines.

46. In an automatic telephone exchange, calling lines, called lines, selecting devices, preselective switches, trunk lines arranged between said preselective switches and said selecting devices in groups and subgroups, trunk lines arranged in groups and subgroups between said selecting devices and said called lines, whereby each of said subgroups of the lines arranged between said preselective switches and said selecting devices corresponds to a subgroup of the said trunk lines arranged between said selecting devices and said called lines.

47. In an automatic telephone exchange, 95 calling lines, called lines, selecting devices, trunk lines arranged between said selecting devices and said called lines, means for testing said trunk lines before they are selected by the selecting device, the trunk lines being arranged in groups and subgroups, and means for testing said subgroups of trunk lines.

48. In an automatic telephone exchange, 105 calling lines, called lines, selecting devices, preselective switches, trunk lines arranged between said preselective switches and said selecting devices, trunk lines arranged between said selecting devices and said called lines, means for testing said trunk lines before they are selected by the selecting devices, said trunk lines being arranged in groups and subgroups and means for testing said subgroups of said trunk lines, before they are selected by the selecting devices.

49. In an automatic telephone exchange, calling lines, called lines, selecting devices, preselective switches, trunk lines arranged between said preselective switches and said selecting devices, these trunk lines being arranged in groups and subgroups, independently movable switches, for testing said lines and said subgroups of trunk lines, trunk lines arranged between said selecting devices and said called lines, independently movable switches for testing said trunk lines, said trunk lines being arranged in

groups and subgroups and independently movable switches for testing said subgroups of said connecting lines.

50. In an automatic telephone exchange, calling lines, called lines, selecting devices, preselective switches, trunk lines arranged between said preselective switches and said selecting devices, these lines being arranged in groups and subgroups, means for testing said lines and means for testing said subgroups of lines, trunk lines arranged between said selecting devices and said called lines, means for testing said trunk lines, said trunk lines being arranged in groups and subgroups, means for testing said subgroups of said trunk lines, and means, whereby said means for testing said trunk lines or said subgroups of lines arranged between said preselective switches and said selecting devices and those means for testing the trunk lines or said subgroups of lines arranged between the preselective switches and the called lines respectively are operated synchronously.
51. In an automatic telephone exchange, calling lines, called lines, selecting devices, selective switches, trunk lines arranged between said preselective switches and said selecting devices, these lines being arranged in groups and subgroups, means for testing said subgroups and lines consisting of automatically moved switches, connecting lines arranged between said selecting devices and said called lines, said trunk lines being arranged in groups and subgroups, and means for testing said subgroups and lines consisting of automatically moved switches.
52. In an automatic telephone exchange, calling lines, called lines, selecting devices, preselective switches, trunk lines arranged between said preselective switches and said selecting devices, these lines being arranged in groups and subgroups, means for testing said subgroups and lines consisting of automatically moved switches, trunk lines arranged between said selecting devices and said called lines, said trunk lines being arranged in groups and subgroups, means for testing said subgroups and lines consisting of automatically moved switches, whereby both kinds of automatically moved switches are operated synchronously.
53. In an automatic telephone exchange, calling lines, called lines, selecting devices, preselective switches, said preselective switches arranged in groups, trunk lines arranged between said groups of preselective switches and said selecting devices, final

selecting devices arranged in groups, trunk lines arranged between said selecting devices and said groups of final selecting devices, means adapted for testing the latter trunk lines before they are selected by said selecting devices, and the arrangement of the trunk lines in such a way, that the number of said trunk lines between said groups of preselective switches and said selecting devices and between said selecting devices and said groups of final selecting devices respectively is equal or greater than the amount of calling lines or called lines respectively.

54. In an automatic telephone exchange, calling lines, called lines, selecting devices, preselective switches, final selecting devices, trunk lines arranged between said preselective switches and said selecting devices, trunk lines arranged between said selecting devices and said final selecting devices, means adapted for testing the latter trunk lines before they are selected by said selecting devices, the arrangement in such a way, that the number of said preselective switches or selecting devices or final selecting devices respectively is equal or greater than the amount of said calling lines.

55. In an automatic telephone exchange, calling lines, called lines, selecting devices, preselective switches, said preselective switches arranged in groups, trunk lines arranged between said groups of preselective switches and said selecting devices, final selecting devices arranged in groups, trunk lines arranged between said selecting devices, and said groups of final selecting devices, means for testing the latter trunk lines before they are selected by selecting devices, and the arrangement of the trunk lines and the preselective switches and the selecting devices and the final selecting devices in such a way, that the number of said trunk lines between said groups of preselective switches and said selecting devices or between said selecting devices and said groups of final selecting devices or of said preselective switches or selecting devices or final selecting devices respectively is equal or greater than the amount of said calling lines or called lines respectively.

In witnesses whereof, I hereunto subscribe my name in the presence of two subscribing witnesses this 16th day of January, 1913.

ARON KATZ.
